UNITED STATES PATENT OFFICE.

MOTT W. McDONALD, OF POLK, OHIO.

MAT-SURFACE PHOTOGRAPHIC PAPER.

SPECIFICATION forming part of Letters Patent No. 593,775, dated November 16, 1897.

Application filed February 1, 1897. Serial No. 621,556. (Specimens.)

To all whom it may concern:

Be it known that I, MOTT W. McDONALD, a citizen of the United States, residing in Polk, in the county of Crawford and State of Ohio, have invented certain new and useful Improvements in Mat-Surface Photographic Papers; and I do hereby declare the following to be a full, clear, and exact description of the invention, such as will enable others skilled in the art to which it appertains to make and use the same.

This invention relates to the art of making photographic or other pictures.

The object is to produce a paper having a perfect mat surface, adapted more particularly for use in connection with the art of embossing photographs, and also in the art of coloring the same, the result attained in the first-named instance being that any cracking of the paper when moistened for the purpose of being brought up in relief will be avoided, and in the second instance the coloring may be readily and evenly applied to the paper with delicate and artistic effect, retaining all the tone of the color or colors.

The invention consists in producing an absolutely glazeless or dead-finish mat surface upon sensitized or other glossy paper.

To carry my invention into effect, I take a sheet of sensitized or other paper, the surface of which may have either a sized, burnished, pronounced glaze, or a so-called "mat" surface—that is, a surface with only a slight glaze or gloss—and grind off the skin or mere surface glazing without removing the body thereof, or grind off the gloss.

The paper may be sized, enameled, or albuminized or be any so-called "mat-surface" paper or any other paper having more or less glaze or gloss, and the grinding operation is to be performed after the paper has been sensitized and before it is printed, toned, and finished, the object being to destroy only its immediate glazed or glossy surface and present a paper having a surface exhibiting a velvety appearance.

The grinding may be effected in many ways, as by employing finely-pulverized pumice-stone, powdered emery, or any other abrasive substance capable of cutting without scratching. An efficient mode of effect-

ing the grinding is to lay the sheet of paper with its back upon a perfectly smooth surface, such as that of plate-glass, sprinkle pulverized pumice-stone or other fine abradant upon the paper, and, the paper being kept or secured in any proper manner against wrinkling, gently but evenly rub it on with the fingers until the glaze or gloss disappears, being careful not to continue the operation longer than necessary merely to get a perfect mat surface—that is, one absolutely free from glaze or gloss.

After the paper has been ground it may then be printed out, toned, and finished, or press-printed, embossed, or colored, or subjected to any one or more of the treatments and operations exerted in producing manufactured art productions, and in all these where the ground paper has been employed the lights and shades will be modified, obviating any sharp, abrupt, or harsh effects and giving a softened appearance.

Besides giving the paper a beautiful, soft, and velvet-like mat surface, the grinding renders the paper more readily expansible and absorbent of moisture for the purpose of embossing or relief work, and the multitudinous retaining-points produced by the cutting action of the abrasive substance particularly adapt the paper for taking colors.

The great advantage of my invention is, with the superior appearance of the product, its great cheapness, utilizing the ordinary photographic paper in general use.

Having thus fully described my invention, what I claim as new, and desire to secure by Letters Patent of the United States, is—

1. As a new article of manufacture, a surface-ground, sized paper, presenting a mat surface, substantially as described.

2. The method of producing paper for photographic pictures, which consists in applying a sensitized surface to sized paper, and then removing the gloss by abrasion, substantially as described.

In testimony whereof I affix my signature in presence of two witnesses.

MOTT W. McDONALD.

Witnesses:

R. G. DYRENFORTH,
R. M. ELLIOTT.
